UNITED STATES PATENT OFFICE.

PAUL BLACKFORD WORTHINGTON, OF NORWALK, CONNECTICUT.

DESIGN FOR A LACE CURTAIN.

54,115.

Specification for Design.

Patented Nov. 4, 1919.

Application filed June 11, 1919. Serial No. 303,490. Term of patent 3½ years.

To all whom it may concern:

Be it known that I, PAUL B. WORTHINGTON, a citizen of the United States, residing at Norwalk, in the county of Fairfield and State of Connecticut, have invented a new, original, and ornamental Design for a Lace Curtain, of which the following is a specification, reference being had to the accompanying drawing, forming part thereof.

The figure shows a picture view of the curtain, illustrating my new design.

I claim:

The ornamental design for a lace curtain, as shown.

PAUL BLACKFORD WORTHINGTON.
